HIGH-FREQUENCY PEST CONTROL DEVICE OR THE LIKE

Arthur J. Droege, Sheboygan, Wis., assignor to
Ultrason-Southern, Inc., Washington, D.C.

Filed Dec. 29, 1972, Ser. No. 319,441

Term of patent 14 years

Int. Cl. D22—06
U.S. Cl. D22—99

FIG. 1

FIG. 2

FIG. 3

FIG. 4

FIG. 5

FIG. 1 is an enlarged perspective view of a high-frequency pest control device or the like embodying my new design;

FIG. 2 is a front elevational view thereof;

FIG. 3 is a back elevational view thereof;

FIG. 4 is a top plan view thereof; and

FIG. 5 is a side elevational view thereof.

The compressor illustrated in broken lines is for illustrative purposes only and does not form a part of the invention.

I claim:

The ornamental design for high-frequency pest control device or the like, as shown and described.
